UNITED STATES PATENT OFFICE.

BENJAMIN WOLHAUPTER, OF NEW ROCHELLE, NEW YORK.

ANTICREEPER.

1,139,391.

Specification of Letters Patent. Patented May 11, 1915.

Application filed February 25, 1911. Serial No. 610,908.

To all whom it may concern:

Be it known that I, BENJAMIN WOLHAUPTER, a citizen of the United States, residing at New Rochelle, in the county of Westchester and State of New York, have invented certain new and useful Improvements in Anticreepers, of which the following is a specification.

The present invention relates to certain new and useful improvements in rail anchors or anti-creeping devices for preventing the longitudinal movement of railway rails.

One of the objects of the invention is the provision of a device of this character which is simple and inexpensive in its construction and comprises few and small parts such as can be cheaply manufactured and assembled.

A further object of the invention is the provision of an anti-creeping device embodying novel features of construction whereby the action of the gripping or biting element is not affected by the expansion and contraction of the rails due to changes in temperature.

A still further object of the invention is the provision of a device of this character which can be easily and quickly applied to or removed from any standard cross section of rail, and which will operate in an effective manner to prevent any longitudinal creeping thereof.

With these and other objects in view, the invention consists in certain combinations and arrangements of the parts as will more fully appear as the description proceeds, the novel features thereof being pointed out in the appended claims.

While I do not wish to restrict myself to any particular form of the invention, yet several embodiments thereof are shown in the accompanying drawings, in which—

Figure 1 is a transverse sectional view through a rail having the improved anti-creeping device applied thereto. Fig. 2 is a sectional view on the line A—A of Fig. 1. Fig. 3 is a transverse sectional view through a rail having a modified form of the anti-creeping device applied thereto. Fig. 4 is a sectional view on the line A—A of Fig. 3. Fig. 5 is a plan view of the rail engaging clip detached. Figs. 6 to 9 are detail views of a still further modification of the invention. Fig. 10 is a transverse sectional view of a rail showing a further modification of the anti-creeping device applied thereto. Fig. 11 is a plan view of the const. act: on

illustrated in Fig. 10. Fig. 12 is a transverse sectional view through a rail having another modification of the invention applied thereto. Fig. 13 is a plan view of the construction shown in Fig. 12. Figs. 14 and 15 are detail views showing a still further possible modification of the invention.

Corresponding and like parts are referred to in the following description and indicated in all the views of the drawings by the same reference characters.

Referring to the drawings, the numeral 1 designates a rail which may be of any suitable cross section and which it is desired to hold against any longitudinal creeping.

In the embodiment of the invention illustrated by Figs. 1 and 2 of the drawings, this rail rests upon a holding member or plate 2, the said plate being rigidly held upon the tie, and formed with a transverse slot 3 which is located under the base of the rail.

The rail engaging member A is in the form of a substantially U-shaped clip having an upper jaw 4 and a lower jaw 5 which diverge from each other. This clip is adapted to be fitted over an edge of the base flange of the rail. The lower jaw 5 of the clip is received loosely within the slot 3 of the holding member or plate 2, and is designed to abut against one of the walls X of the slot. The clip jaws may be substantially square or angular in cross section, and loosely receive the flange of the rail when the clip is in an upright position. However, this clip is designed to be held yieldingly in a position canted from its vertical plane, as indicated more clearly in Fig. 2, so that the angular edges on the inner faces of the jaws will bite into the surfaces of the rail flange and provide a positive holding engagement therewith. The means for canting this rail-engaging clip from the vertical may be a spring arm 6, or its equivalent, which as illustrated in Figs. 1 and 2, projects laterally from the upper jaw 4 of the clip and is curved downwardly so as to bear against the upper surface of the base flange of the rail. This spring 6, or its equivalent, before being applied to the rail flange normally will take the position shown in dotted lines in Fig. 2, when being applied to the flange the clip is tilted slightly and the spring 6 is forced into the position shown in full lines. Hence, the spring action of this arm serves to hold the clip tilted or canted so as to cause the an-

gular edges of the jaws to securely grip the flange of the rail, and the upper face of the lower jaw 5 of the clip may be transversely serrated to provide the teeth 11 for producing a more positive engagement with the rail. Should there be any tendency of the rail to creep in the direction of the arrow upon Fig. 2, the lower jaw 5 of the clip would engage the wall X of the slot 3 so as to hold the rail against such movement, and at the same time the action of the wall X of the slot against the clip would cause the clip to bite more strongly into the rail and take a firmer hold thereon. In case the rail moved longitudinally in the opposite direction, the clip would move therewith until the lower jaw thereof came into contact with the opposite wall of the slot 3. The pressure of the said wall against the lower arm of the clip would then tend to reduce the biting action of the clip and to loosen it so that the rail could move backward independently thereof. However, the spring canting arm 6 would always retain the clip in a positive engagement with the rail so that upon the reverse movement of the rail the clip would again be brought into contact with the wall X of the slot and act as previously explained to prevent creeping of the rail. Should it be desired that the clip remain permanently at one point upon the rail, the opening 3 in the plate would be made sufficiently large so that the lower arm of the clip would not be brought into contact with the wall of the slot 3 located opposite the wall X thereof.

In Figs. 3, 4, and 5 of the drawings, a modification is shown in which the spring arm 6^a is applied to the lower jaw 5 of the rail engaging clip A instead of to the upper jaw. It will be obvious, however, that this spring arm 6^a will bear against the bottom of the rail so as to cant the clip and cause it to bite into and positively grip the flange of the rail as in the previous instance.

A further modification is shown in Figs. 6, 7, 8 and 9 in which the canting means is not carried by the rail engaging member, but is separate and detachable therefrom. The body portion of the rail engaging member A is substantially as previously described, and a removable key 8 is designed to be inserted between the rail and one jaw 5 of the clip for holding the said clip in a canted position. This key 8 is shown as consisting of a spring strip which is suitably crimped to provide an inclined portion 8^a. When the spring strip is flattened out under pressure it can readily be inserted in position. This will be readily apparent by reference to Fig. 8, in which figure the rail engaging clip is shown in an upright position and the spring strip flattened out for insertion between the upper jaw of the clip

and the base flange of the rail. After the spring strip has been inserted and released, it again resumes the shape shown in Fig. 6, and the inclined portion 8^a thereof serves to hold the rail engaging clip yieldingly in a canted position so that the edges thereof bite into and positively engage the flange of the rail.

A further modification is shown in Figs. 10 and 11 in which the lower jaw 5 of the rail engaging clip A is formed with an extension 5^a which projects under the base of the rail and is provided at its extremity with a curved hook-arm 9 adapted to be sprung over the opposite edge of the rail base. In this embodiment the upper jaw 4 of the rail engaging clip is formed with a spring canting arm 6 similar to that shown in Figs. 1 and 2. Owing to the fact that the jaws of the clip loosely receive the base flange of the rail, the device can be readily tilted into the position indicated by dotted lines on Fig. 10 when being applied to the rail, and subsequently forced upwardly so as to cause the curved arm 9 to spring over the edge of the rail.

Figs. 12 and 13 illustrate a slight variation from the construction shown in Figs. 10 and 11, the extension 5^a of the lower jaw 5 projecting beyond the opposite edge of the rail flange, where it is curled upwardly at 10, so as to have a spring engagement with the upper opposite edge of the rail base as in the previous instance.

In the modification shown in Figs. 14 and 15, the extension 5^a of the lower jaw of the clip is backturned at 11, the said backturned portion being provided upon its lower face with a depression 11^a designed to engage the edge of the rail flange when the device is in operative position. The canting means here shown consists of a V-shaped spring member 12 which is inserted between the extension 5^a and the base of the rail. Should the rail have a tendency to creep, the lower jaw of the clip becomes engaged by the said tie and the clip would then operate as has been previously described to force the same into a firmer engagement with the rail so as to grip the rail and prevent longitudinal movement thereof. In this form of the invention, that is, the one shown in Figs. 14 and 15 of the drawings, it will be observed that the backturned end 11 of the clip bar is so disposed as to provide between the same and the extension 5^a a pocket 13 of sufficient depth laterally and vertically to readily admit of the clip being placed over and disengaged from the rail flanges. When the holding spring 12 is not in place, it will be observed that sufficient play is admitted within the clearance pocket 13 so that the clip bar can be moved laterally upon the rail flanges to readily engage and disengage the jaw elements 4 and 5.

My invention is susceptible to many other variations and modifications which can be made without departing in any manner from the spirit thereof, and I do not restrict myself to the specific embodiments illustrated by the accompanying drawings and described herein.

The essential feature of the invention resides in the canted rail engaging clip, and any means might be utilized for holding the clip in this canted position.

I claim:

1. An anti-creeping device including a member having angular edges adapted to grip the rail base flange when the member is canted, and yielding means for normally holding said member canted from a vertical plane.

2. An anti-creeping device including a clip adapted to loosely receive the base flange of a rail and having one of the jaws thereof provided with teeth, and a spring arm projecting laterally from one of the jaws, the said spring arm loosely engaging the rail to cant the clip and cause the same to grip the rail.

3. An anti-creeping device including a clip adapted to loosely receive the flange of a rail, the jaws of the clip being formed with angular corners and one of the jaws being provided with transverse serrations to form teeth, and yielding means for canting the clip to cause the same to grip the rail.

4. An anti-creeping device including a clip adapted to loosely receive the base flange of a rail, the jaws of the clip being formed with angular edges and the lower jaw being provided with transverse serra-

tions forming teeth, and a spring arm projecting laterally from the upper jaw and 40 bearing loosely against the rail to hold the clip in a canted position.

5. An anti-creeping device including a clip designed to receive the base flange of a rail, and a holding plate formed with a slot 45 receiving the lower arm of the clip, the engagement of the said arm of the clip with a wall of the slot tending to cant the clip so as to cause the same to grip the rail.

6. An anti-creeping device including a 50 clip adapted to be applied to the base flange of a rail, means for normally holding the clip in a canted position for causing the same to grip the rail, and a holding plate formed with a slot receiving the lower arm 55 of the clip, the engagement of the said lower arm of the clip with one of the walls of the slot tending to cause the clip to grip the rail more firmly.

7. An anti-creeping device including a 60 clip adapted to be applied to the base flange of a rail, a spring arm projecting from one of the jaws of the clip and bearing against the rail to hold the clip yieldingly in a canted position, and a holding plate formed 65 with a slot receiving the lower jaw of the clip, the said clip being forced into a firmer engagement with the rail when caused to bear against one of the walls of the slot.

In testimony whereof I hereunto affix my 70 signature in the presence of two witnesses.

BENJAMIN WOLHAUPTER.
